DIAMOND WHEEL DRESSER

Emil Brocker, Van Dyke, Mich., assignor to Super Tool Company, Warren Township, Macomb County, Mich., a partnership

Application February 3, 1944, Serial No. 520,914

1 Claim. (Cl. 51—34)

1

This invention relates to dressing devices and particularly to a motor driven dressing wheel and its adjustable support by which angularly disposed faces are dressed upon grinding wheels.

Difficulty has been experienced in the past when attempting to dress the face of a diamond grinding wheel at an angle other than at right angles to its plane of rotation. Since diamond impregnated grinding wheels are now being used extensively for grinding threads and other forms requiring a predetermined angular face on the wheel, no means has heretofore been provided for accurately dressing the impregnated wheel in a simple operation.

The present invention embodies a dressing device having a base and a platform which are joined together by a pintle about which the platform may be adjusted at any angle relative to the base. The base is constructed of steel, or other magnetic material, so as to be supported on a magnetic table and is provided with apertures by which it may be bolted to tables or other types of grinding machines. The platform supports a cradle on which a motor is secured and a lead screw advances the cradle on the platform against the bias of a spring.

The motor shaft is connected through a universal driving element to a shaft which is mounted in bearings in the end of the motor housing. The shaft receives the stem of the dressing wheel to which it is secured by suitable clamping means. The motor is preferably reversible so as to operate the dressing wheel in a direction opposite to the direction of rotation of the grinding wheel. The relative direction of rotation of the dressing wheel changes when the dressing wheel is swung from one to the other side of the central plane of the grinding wheel. The motor is preferably of the high speed type, operating at approximately 6,000 R. P. M. and developing substantially $\frac{1}{6}$ of a horsepower.

Clamping means are provided on the base by which the pintle is secured after the angular position of the platform has been adjusted. An index scale is provided on the wall of the pintle by which the angular position may be set or checked. The pintle is positioned near one end of the platform and base, ahead of the motor, so as to have the dressing wheel disposed approximately in line with the pintle axis.

Accordingly, the main objects of the present invention are: to provide a dressing device with a base by which it is attached to a table and with a platform having a pivotal connection with the base, on which a motor is advanced and retract-

2

ed; to join a platform to a base by a pintle about which they are angularly adjusted and mount a motor for axial movement on the platform; to mount a motor for axial movement on the top of a platform and provide a lead screw therebelow for moving the motor, all of which is supported by a pintle on a base which is attachable to a table of a grinding machine adjacent to the wheel to be dressed; and, in general, to provide a dressing device for dressing angular faces on a diamond impregnated grinding wheel, which is simple in construction, positive in operation and economical of manufacture.

Other objects and features of novelty of this invention will be specifically pointed out or will become apparent when referring, for a better understanding of the invention, to the following description taken in conjunction with the accompanying drawings, wherein:

20 Figure 1 is a perspective view of a dressing device embodying features of this invention;

Fig. 2 is a broken sectional view of the structure illustrated in Fig. 1, taken along line 2—2 thereof;

Fig. 3 is a sectional view of the structure illustrated in Fig. 2, taken on the line 3—3 thereof;

Fig. 4 is a view of the structure illustrated in Fig. 2 as observed from the line 4—4 thereof; and,

Fig. 5 is a broken view of structure similar to that illustrated in Fig. 2, showing a modified form 30 thereof.

The dressing device of the present invention embodies a base 10 which is made of magnetic material so as to be securable in fixed position, when mounted upon a magnetic chuck of a grinding machine table. The base is also provided with bolt receiving recesses 12 by which the device may be securely clamped to non-magnetic tables of other types of machines. Threaded apertures 14 are also provided in the base by 40 which the base may be secured to tables of still other types of machines having bolts with which the apertures are aligned.

The base has a pintle 16 secured thereto for angular adjustment thereon. The pintle is provided with trunnions 18 and 20, the latter of which projects within an aperture 22 of a truncated conical plate 24, which mates within the truncated conical aperture 26 at the forward end of the base 10. A pair of screws 28 clamp the pintle 16 to the plate 24 to provide frictional engagement therebetween. The trunnion 18 projects into an aperture 30 of a platform 32 which is secured to the pintle by a plurality of screws 34. The platform is adjustable with the pintle on the base 10, the adjustment being set or checked

by an index scale 36 on the pintle surface from index marks 38 on the base. The scale may extend from 0° to 90° and from 90° back to 0°, so that the index marks 38 may be disposed on both sides of the base and at the front edge halfway therebetween. By constructing the scale in this manner, the setting may be read on either side or at the front of the device.

The platform has a gib 40 machined thereon and a second gib 42 is secured in position by a plurality of screws 44. The gibs encompass a dove tail base 46 on a carriage 48 on which a motor 50 is secured by a plurality of screws not herein illustrated. The carriage supports a pin 52 which is secured in position by a screw 54. The pin operates in a slot 56 extending through the platform 32. The end of the pin has a projecting finger 58, brazed or otherwise secured thereto, which is made of extremely hard material to prevent wear. The pin projects within a helical slot 60 disposed in a cylinder 62, the ends of which are mounted in brackets 64 supported on the underside of the platform 32 by the screws 66. A shaft 68 on the cylinder 62 is journaled in the brackets 64 on the end of the platform opposite to that to which the pintle 16 is attached. The shaft 68 is connected by a block 70 to an operating handle 72. When the handle is operated to rotate the shaft 68, the helical slot 60 causes the projection 58 and pin 52 to move axially of the cylinder 62 to thereby advance the carriage 48 toward the end of the platform to which the pintle 16 is attached.

The motor is of conventional form, being of the reversible type and operating at approximately 6,000 R. P. M. when developing substantially $\frac{1}{8}$ of a horsepower. It is to be understood that non-reversing motors and those of higher and lower speeds and horsepower ratings may be employed in place of the motor having the particular characteristics outlined above. The motor 50 comprises a casing 76, a stator and rotor (not shown) from which a shaft 78 extends from the forward end. The forward end of the casing is enclosed by a bracket 80 having a bearing supporting element 82 in the left-hand end for supporting a bearing 84 near the end of the shaft 78. A pair of bearings 86 are mounted near the front end of the bracket for engaging a dressing wheel supporting shaft 88.

Collars 90 are mounted on the adjacent ends of the shafts 78 and 88, having on their adjacent faces a pair of projecting pins 92, the planes through those on each collar being offset 90° to each other. The pins project into apertures in a resilient disc 94 made of rubber, leather, or similar flexible material. The disc provides universal connection between the two shafts and prevents vibration from being transferred from the motor to a grinding disc 95. The grinding disc 95 is supported on a shaft 96 which projects from the shaft 88 and is retained in clamped position by a screw 98. The bearings 86 are retained in spaced relation by a collar 100 and are maintained in forward position by a split washer 102.

The platform 32 has a U-shaped slot 109 cut in its top surface extending from the left hand end, as viewed in Fig. 2, toward the pintle 18. A spring 111 operates within the slot 109 one end being secured to a pin 112 projecting from the under surface of the dovetailed base 46, the other end being secured by a pin 113 which extends across the metal at the end of the slot. The tension in the spring urges the platform 48 to the left, which movement is interrupted by the stop plate 114 secured by screw 115 to the end of the platform 32.

A split tube 116 encompasses the cylinder 62 when the ends are supported in recesses 117 provided in the brackets 64. The projecting finger 58 extends in the slot in the tube in which it moves as the platform 48 is advanced or retracted. Between the gib 42 and the dovetailed base 46 an adjusting shim 119 is provided for taking up any wear which may occur between the gibs and the base. Screws 121 projecting through the gib 42 adjust the position of the shim and after the adjustment has been made the screws are locked in adjusted position by the nuts 122.

A clamping screw 123 is provided in the base, which operates directly upon the plate 23, or through a brass plug, to prevent the marring of the truncated conical surface thereof, when securing the plate to the base when the platform is adjusted. To prevent grinding particles from falling into the movable parts of the device and causing unnecessary wear, a cover element 124 is secured to the platform 48 by the screws 125. The element extends over the top and sides of the platforms and therebeyond, to maintain the platform 32 covered when the platform 48 is in advanced position.

When it is desired to dress a diamond impregnated wheel of a grinding machine, the base 10 is first placed upon the table of the machine and secured in predetermined position thereon by suitable means which may be a magnetic chuck, bolts, screws, clamping bars, or any other means suitable for retaining the base firmly secured to the table. The axis of the base is preferably disposed parallel to the direction of movement of the table so that the base may be oriented relative to the grinding wheel and the dressing wheel may be set off to a desirable angle by the use of the scale 36. After the device has been accurately set, the motor 50 and dressing wheel 94 are operated at high speed and the wheel of the grinding machine is rotated, the wheels at their point of engagement operating in opposite directions. The carriage of the machine is adjusted to bring the wheel into desired position and is advanced at an angle across the face to be dressed by the manipulation of the handle 72. After a face is dressed to a predetermined angle on one side of the wheel, the platform 32 is moved angularly on the base to bring the wheel into position on the opposite side of the grinding wheel. The motor 50 is reversed to have the wheels operating at their point of engagement in opposite directions and the handle 72 is manipulated to pass the dressing wheel across the grinding wheel face. After the dressing operation, the device may be removed from the carriage by the simple expedient of interrupting the current to the magnetic chuck, or by removing the bolts, or other clamping means, which retained the base in secured position.

In Fig. 5 a modified form of support for the dressing wheel shaft 127 is illustrated, that wherein the bearings are loaded with a predetermined pressure. The shaft is mounted in a pair of oppositely disposed thrust bearings 128 and 129 supported in a housing 131. A nut 132 is threaded on the shaft 127 while a nut 133 is threaded to the inner surface of the housing 131. The bearings are spaced by a sleeve 134 through which the shaft 127 extends. When the nut 133 is tightened the pressure is applied through the outer to the inner raceway of the bearing 128 through the sleeve 134 to the inner and outer raceway of the bearing 129 to preload the bearings. The adjustment of the nut 132 retains the shaft 127 against longitudinal movement relative

tive to the bearings. The universal drive connection through the rubber or like element 94 is provided between the motor shaft and the shaft 121.

What is claimed is:

A dressing device including, in combination, a motor, a support for said motor, a platform on the top of which said support is movable, means on the underside of said platform for moving said support, a spring for returning said platform to its initial position, a base, a pivot joining said base and platform forwardly of said motor, a shaft mounted forwardly of said motor and supported thereby, and a universal connector joining said shaft to said motor.
